(57) **CLAIM**

The ornamental design for a key for vehicle, as shown and described.

DESCRIPTION

FIG. 1 is a front elevational view of a key for vehicle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof; and,

FIG. 8 is a rear perspective view thereof.

The dark and light grayed surfaces shown on the surface of the design drawings do not represent a color nor a design pattern and only represent shading features on the surface of the ornamental design.
